J. B. LESSELL

MANUFACTURE OF ORNAMENTED WARE

Filed April 13, 1923

Invantor,
John B. Lessell
by G. H. Harvey,
attorney.

UNITED STATES PATENT OFFICE.

JOHN B. LESSELL, OF ZANESVILLE, OHIO, ASSIGNOR TO THE LESSELL COMPANY, OF ZANESVILLE, OHIO, A CORPORATION OF OHIO.

MANUFACTURE OF ORNAMENTED WARE.

Application filed April 13, 1923. Serial No. 631,873.

To all whom it may concern:

Be it known that I, JOHN B. LESSELL, a citizen of the United States, residing at Zanesville, in the county of Muskingum and State of Ohio, have invented new and useful Improvements in the Manufacture of Ornamented Ware, of which the following is a specification.

My invention relates to the ornamentation of ware and its object is to produce ornamentation upon glass or upon the bisque, matt or glazed surfaces of pottery or enamelled or other metal or other suitable material.

Referring to the accompanying drawing, I show a dish in plan view with certain sections thereon at different steps of the manufacturing process, a portion being broken away.

The dish has its central portions protected by the cover F. The rim A, shown in natural color in section 1, is sprayed or otherwise coated with a paint B of the desired color and other preferred characteristics, as shown on section 2. A print or transfer C is placed on the coat of paint, as shown on section 3; and the transfer C and more or less of the surrounding portions, if desired, is covered with a coat of paint D of the

desired color characteristics, as shown on section 4. The dish, when provided with the desired coats and prints, is placed in a kiln or muffle or the like and burned or fired in order to fuse the coats B and D together and

to fuse the coat B to the dish. The print or transfer C is made of a substance which will not fuse with the coats B and D at the kiln or muffle temperatures. After the dish has become sufficiently cool it is removed

from the kiln or muffle, and the print and such parts of the coat D as is above the print are easily brushed off or otherwise removed, leaving the surrounding parts and the parts beneath the place occupied by the print, with

the coloration due to the characteristics of the paint, as shown in section 5. The depression left after brushing off the print C and the coat D above it will have the configuration of the print.

The coat B may be omitted and the print or transfer C may be placed directly on the dish. Then a coat of paint may be sprayed upon the print and such surrounding parts as desired. After the firing operation, the transfer and the paint on the same will be

removed, leaving the configuration of the print on the dish, which may be transparent, translucent, or opaque. The parts around this configuration will have the colors given to them by the paint alone or by its combination with other paint in the dish-color beneath. If desired the coat D may cover only portions surrounding the print, or may overlap it more or less, as the print C can be brushed away easily whether or not the coat D overlies it.

The operations described are substantially the same for applications to glass, or glazed, bisque or matt surfaces on pottery, or to enamelled metal or other metal. I may, as in 70 decorating a vase, spray an initial coat of paint thereon as a background, and apply one or more coats of paint thereon, before or after the print or transfer has been applied or both, the blending and interaction of the coats during firing bringing out the lustre and colors to form a decoration design more uniform than found on the usual hand-decorated vase. To illustrate, a background of orange paint may 80 be applied to a vase. On this when dry may be placed a non-fusible black pigment of a chosen design. A final coat of black may cover the orange ground color and the print, also, if desired. After firing, the non- 85 fusible print and the coat thereon, if any, are brushed off, leaving the design of the print on the orange background, while the surrounding parts have distinctive colorations due to the relative varying depths of 90 the orange and black coats.

In preparing the said material which will not fuse with the coat B or the coat D, I may use boron, or carbon, or both in finely divided condition mixed with a binder such 95 as linseed oil, for example. However, I do not limit this invention to these elements, as other materials having a high fusing point may be used.

I claim—

1. The method of treating the surfaces of glass, pottery, porcelain, metal, and like articles, which consists in applying to the article, a material of selected outline which will not fuse, applying thereon and over the said material a fluid containing the desired coloring matter, firing the article to fuse the coloring matter, and then removing the said material and coloring matter thereon from the article.

110

2. The method of treating the surfaces of glass, pottery, porcelain, metal, and like articles, which consists in applying to the natural surface of the article, a ground coat 5 of fusible paint, applying thereto a material of selected outline which will not fuse, applying thereon and over the said material, a fluid containing the desired coloring matter, firing the article and then removing the 10 said material and coloring matter thereon.

3. The method of treating the surfaces of glass, pottery, porcelain, metal, and like articles, which consists in applying to the article, a material of selected outline which 15 will not fuse, spraying thereon and over the said material a fluid containing the desired coloring matter, firing the article to fuse the

coloring matter, and then removing the said material and coloring matter thereon from the article. 20

4. The method of treating the surfaces of glass, pottery, porcelain, metal, and like articles, which consists in applying to the natural surface of the article, a ground coat 25 of fusible paint, applying thereto a material of selected outline which will not fuse, spraying thereon and over the said material, a fluid containing the desired coloring matter, firing the article and then removing the said material and coloring matter thereon. 30

Signed at Zanesville, Ohio, this 31st day of March 1923.

JOHN B. LESSELL.
